CORN KERNEL REMOVER

Earl C. Carruthers, 6651 SW. 45th St.,
Fort Lauderdale, Fla.

Filed July 26, 1960, Ser. No. 61,519

Term of patent 14 years

(Cl. D44—29)

FIG. 1.

FIG. 2.

FIG. 3.

FIG. 4.

FIG. 5.

Figure 1 is a plan view of a corn kernel remover, showing my new design,

Figure 2 is a bottom plan view thereof,

Figure 3 is a side elevation thereof,

Figure 4 is an end view of the corn kernel remover and,

Figure 5 is an end view from the opposite direction to that indicated in Figure 4.

I claim:

The ornamental design for a corn kernel remover, as shown.
